UNITED STATES PATENT OFFICE.

WILLIAM CASE, OF CHICAGO, ILLINOIS, ASSIGNOR TO THE NATIONAL
MALLEABLE CASTINGS COMPANY, OF CLEVELAND, OHIO.

DRAFT-RIGGING FOR CARS.

SPECIFICATION forming part of Letters Patent No. 643,590, dated February 13, 1900.

Application filed April 11, 1898. Serial No. 587,114. (No model.)

To all whom it may concern:

Be it known that I, WILLIAM CASE, of Chicago, in the county of Cook and State of Illinois, have invented a new and useful Improvement 5 in Draft-Rigging for Cars, of which the following is a full, clear, and exact description, reference being had to the accompanying drawings, forming part of this specification, in which—

10 Figure 1 shows my improved draft-rigging, partly in plan view and partly in horizontal central section. Fig. 2 is an elevation of the inner side of one of the draft-irons. Figs. 3 and 4 are vertical cross-sections on the lines 15 III III and IV IV, respectively.

In the drawings, 2 2 represent the draft-irons, which are set parallel to each other and are secured to the draft-timbers of the railway-car. Near the ends of the draft-irons 20 and fitting in opposite lugs or recesses 3 on the inner faces thereof are stop-plates 4, (shown clearly in Figs. 1 and 2,) which are confined in place by cross-bolts 5 5, passing through them and through the draft-irons.

25 These stop-plates have central holes 6, through which project the ends of followers 7 7', which have central holes and at the inner ends are formed with annular heads 8, against which the end of the spring 9 bears. This spring,

30 which may conveniently be double, consisting of two concentric parts, is placed between the draft-irons and is confined in place by annular retaining-flanges 10 at the outer margins of the follower-heads. The location of 35 the flanges at the outer margins is important, because it leaves the central holes of the followers open and unobstructed for the passage of a tail-bolt through the followers and through the axis of the spring when it is de-

40 sired to use a tail-bolt. When a U-shaped strap is to be used instead of a tail-bolt, the middle portion of the strap fits against the outer end of the rear follower 7' and the legs of the strap extend between the draft-irons 45 above and below the spring to the end of the draw-bar, to which they are bolted in the usual way. I believe I am the first thus to provide a draft-rigging capable of use as well

with a tail-bolt as with a strap, and the great utility of such construction will be appreciated by those skilled in the art. 50

The operation of the device will be readily understood. In buffing the draw-bar presses upon the follower 7 and moves it against the spring, and in pulling the draw-bar, acting 55 through the strap or tail-bolt, draws the follower 7' forward and compresses the spring in the opposite direction.

An important advantage of the construction described above is that when it is desired to remove the draft-rigging to repair a broken spring or follower it can be done easily 60 without detaching the draft-irons from the timbers or dismantling or injuring the timbers themselves, as is the case when devices 65 known and used heretofore are employed. To remove the draft-rigging, it is only necessary to loosen and withdraw the bolts 5 5 and then to draw the stop-plate, with the followers and spring, vertically from between 70 the draft-irons—an operation which can be done rapidly and without injury to any of the parts.

Within the scope of my invention changes 75 in the form and construction of the parts may be made, since

What I claim is—

1. In a draft-rigging, stop-plates set against lugs or recesses on the draft-irons and removable vertically therefrom, said stop-plates being adapted to contain between them the followers and spring, and means whereby the stop-plates are secured to the draft-irons. 80

2. In a draft-rigging, stop-plates set against lugs or recesses on the draft-irons and removable vertically therefrom, said stop-plates being adapted to contain between them the followers and spring, and horizontal bolts, whereby the stop-plates are secured to the draft-irons. 85

In testimony whereof I have hereunto set my hand.

WILLIAM CASE.
